UNITED STATES PATENT OFFICE.

BIGE GREGORY, OF VERNON, TEXAS, ASSIGNOR OF SEVEN-SIXTEENTHS TO G. W. LISEN-BEE AND ONE-EIGHTH TO M. G. POTEET, BOTH OF VERNON, TEXAS.

MAIZE HEADER.

Application filed July 18, 1927. Serial No. 206,571.

The present invention relates to a maize header and aims to provide an efficient and reliable structure for heading maize and the like by severing the heads from the stalks and conveying said heads upwardly into a receptacle or the like.

Another important object of the invention lies in the provision of a structure of this nature wherein a plurality of rollers are arranged in pairs and one of the rollers of each pair is movable away from the other for closing an electric circuit to cause the release of a latch so that a spring-actuating knife may cut the stalk.

15 A still further important object of the invention resides in the provision of a structure of this nature which is simple, compact, convenient, accessible, not likely to easily become out of order, and otherwise well adapted to 20 the purpose for which it is designed.

With the above and numerous other objects in view as will appear as the description proceeds, the invention resides in certain novel features of construction, and in the combination and arrangement of parts as will be hereinafter more fully described and claimed.

In the drawing:

Figure 1 is a fragmentary top plan view showing the forward portion of the machine,

30 Figure 2 is a vertical longitudinal section through the forward portion of the machine,

Figure 3 is a side elevation of the forward portion of the machine,

Figure 4 is an enlarged detail top plan view 35 of a portion of the machine,

Figure 5 is a perspective view of the rear portion of the machine,

Figure 6 is a perspective view of one of the rollers,

40 Figure 7 is a perspective view of one of the knives,

Figure 8 is a perspective view of one of the gears for the knives.

Referring to the drawing in detail, it will 45 be seen that the letter F denotes a frame formed of channel irons having a front cross member 5, sides 6 extending rearwardly therefrom, and merging into inwardly and rearwardly converging end portions 7 which 50 are attached at their extremities to a beam 8 by suitable means 9. Wheels 10 are mounted on axles 11 projecting from the sides 6 of the frame and have annular gears 12 attached thereto concentrically therewith and formed 55 with outer and inner teeth.

A plurality of fingers 14 have depending bracket portions 15 attached by means of bolts 16 or in any other suitable manner to the front portion 5 of the frame F. Thus the fingers are disposed above the frame and project forwardly thereof and terminate in points as is clearly illustrated in Figures 1 and 4. These fingers are adapted to receive the maize stalks therebetween as the machine moves forwardly. Rollers 17 and 18 are 60 mounted on the fingers being arranged in pairs, one roller 17 and one roller 18 in each pair. The rollers 17 are mounted for rotation in bearings 19 which are rigidly mounted on the fingers and have operatively connected 65 therewith spiral gears 20 meshing with spiral gears 21. The rollers 18 have rigid pintles 22 at their forward ends which are journaled in bearings 23 having bolts 24 depending therefrom through slots 25 in the fingers. Stop 70 lugs 26 rise from the fingers and have openings to receive stems 27 from the bearings and springs 28 are disposed about the stems impinging against the bearings and the stop lugs to hold the bearings 23 in predetermined 75 positions. The rear ends of the rollers 18 have sockets 29 with notches 30 radiating therefrom and pintles 31 are receivable in the sockets and have radiating keys 32 receivable in the notches 30 so that the rollers 23 may be 80 rocked to one side at their forward ends. The pintles 31 are journaled in fixed bearings 33. On each pintle 31 there is a spiral gear 34 meshing with a spiral gear 21. Each spiral gear 21 is mounted on a shaft 35 journaled in 85 the frame portion 5 and having a beveled gear 36 on its lower end meshing with a bevel gear 37 on a shaft 38 journaled through the side portions 6 of the frame and having gears 39 90 on its extremities which mesh with the internal teeth of the annular gears 12. A spiral spring 40 is mounted on each shaft 35 above the frame and has one end fixed to the shaft and the other end fixed to a knife 41 fixed on a gear 42 by means of screws 43 or in any other 95 suitable manner. This knife 41 has a projecting portion 44. A latch 45 is pivoted in a bracket 46 and a spring 47 is provided for the disengagement of the latch 45 from the gear 42.

The brackets 46 extend downwardly from a platform 49 mounted across the frame immediately to the rear of the upper portion of the frame member 5. An electro-magnet 50 is mounted on the platform 49 and when en- 110

ergized, attracts the free end of the latch so as to engage the same with the gear 42. An arm 53 is mounted on each bearing 23 and has a contact 54 thereon engageable with a contact 55 on a bracket 56. The springs 28 normally hold the bearing 23 so that the contacts 55 are spaced from the contact 54 and these contacts 54 and 55, therefore are in open circuit with their respective electro-magnets 50. 10 When the machine moves along and the stalks pass between the rollers it will be seen that the rollers 18 will be swung away from the rollers 17 so as to close the circuits, to energize the electro-magnets 50 to engage the latches from the gears 42 thus causing the springs 40 to be wound up so that the knives rotate very quickly when once released and insure severing of the main stalks.

It will be noted from Figure 5 that the beam 20 is extended rearwardly and has a platform 60 on the rear end thereof. The wheel 61 is journaled in a fork 62 from which extends a vertical shaft 64 journaled through the rear portion of the beam immediately in front of the platform. A whiffletree 65 is mounted on the beam immediately forward of the shaft 64. A handle 66 for steering purposes is mounted on the upper end of the shaft 64.

An endless conveyor 68 is trained about 30 rollers 69, one of which is journaled between the sides 6 and the other of which is journaled in brackets 70 rising from the rear ends of the sides 6, so that the rungs of the endless conveyor incline upwardly and rearwardly. 35 This endless conveyor receives the maize heads from the platform 49.

It is apparent that the maize heads may be gathered in receptacles, or the like at the elevated end of the conveyor.

It is thought that the construction, operation, utility, and advantages of this invention will now be quite apparent without a more detailed description thereof. The present embodiment of the invention has been disclosed in detail merely by way of example since in actual practice it attains the features of advantage enumerated as desirable in the statement of the invention and the above description. It is apparent that changes in the details of construction, and in the arrangement of parts may be resorted to without departing from the spirit or scope of the invention as hereinafter claimed or sacrificing any of its advantages.

It is to be noted that the lower and forward roller 69 of the endless conveyor structure has a gear 72 operatively connected therewith and meshing with the external teeth of the gears 12 on the wheels.

Having thus described my invention, what I claim as new is:

1. In a maize header of the class described, a wheeled frame, a plurality of fingers projecting forwardly from the frame, a plurality of rollers mounted on the fingers, said roll-

ers being arranged in pairs, means for journaling one roller of each pair so that its axis is rigid, means for journaling the other roller of each pair so that the forward end of its axis may be swung to one side, circuit closers 70 operable by the movements of the second mentioned rollers of the pairs, knives, and means for controlling the operation of the knives from the circuit closers.

2. In a maize header of the class described, 75 a wheeled frame, a plurality of fingers projecting forwardly from the frame, a plurality of rollers mounted on the fingers, said rollers being arranged in pairs, means for journaling one roller of each pair so that its axis is rigid, means for journaling the other roller of each pair so that the forward end of its axis may be swung to one side, circuit closers operable by the movements of the second mentioned rollers of the pairs, 85 shafts journaled in the frames, gearing between the shafts and the rollers, gears on the shaft, knives on the gears of the shafts, springs on the shafts having one end fixed to the shaft and the other end fixed to the knives, 90 pivotally mounted latches engaging the gears on the shaft to normally hold them stationary, spring means associated with the latches to hold them engaged with the gears, and electromagnetic means in circuit with the 95 switches for releasing said latches when the latter of the pairs of rollers are swung.

3. In a maize header of the class described, 100 a wheeled frame, a plurality of fingers projecting forwardly from the frame, a plurality of rollers mounted on the fingers, said rollers being arranged in pairs, means for journaling one roller of each pair so that its axis is rigid, means for journaling the other roller of each pair so that the forward end of its 105 axis may be swung to one side, circuit closers operable by the movements of the second mentioned rollers of the pairs, shafts journaled in the frames, gearing between the shafts and the rollers, gears on the shaft, knives on the 110 gears of the shafts, springs on the shafts having one end fixed to the shaft and the other end fixed to the knives, pivotally mounted latches engaging the gears on the shaft to normally hold them stationary, spring means 115 associated with the latches to hold them engaged with the gears, and electromagnetic means in circuit with the switches for releasing said latches when the latter of the pairs of rollers are swung, an endless inclined conveyor 120 or mounted in the frame to receive the heads after they are severed from the stalks.

4. In a maize header of the class described, 125 a wheeled frame, a plurality of fingers projecting forwardly from the frame, a plurality of rollers mounted on the fingers, said rollers being arranged in pairs, means for journaling one roller of each pair so that its axis is rigid, means for journaling the other roller of each pair so that the forward end 130

of its axis may be swung to one side, circuit closers operable by the movements of the second mentioned rollers of the pairs, shafts journaled in the frames, gearing between the 5 shafts and the rollers, gears on the shaft, knives on the gears of the shafts, springs on the shafts having one end fixed to the shaft and the other end fixed to the knives, pivotally mounted latches engaging the gears on the 10 shaft to normally hold them stationary, spring means associated with the latches to hold them engaged with the gears, and electromagnetic means in circuit with the switches for releasing said latches when the latter of 15 the pairs of rollers are swung, an endless inclined conveyor mounted in the frame to receive the heads after they are severed from the stalks, a beam extending rearwardly from the frame, and dirigible wheel means supporting the rear end of the beam.

5. In a maize header of the class described, a wheeled frame, a plurality of fingers projecting forwardly from the frame, a plurality of rollers mounted on the fingers, said rollers being arranged in pairs, means for journaling one roller of each pair so that its axis is rigid, means for journaling the other roller of each pair so that the forward end of its axis may be swung to one side, circuit closers 20 operable by the movements of the second mentioned rollers of the pairs, shafts journaled in the frames, gearing between the shafts and the rollers, gears on the shaft, knives on the gears of the shafts, springs on the shafts having one end fixed to the shaft and the other end fixed to the knives, pivotally mounted latches engaging the gears on the shaft to normally hold them stationary, spring means 25 associated with the latches to hold them engaged with the gears, and electromagnetic means in circuit with the switches for releasing said latches when the latter of the pairs of rollers are swung, an endless inclined conveyor mounted in the frame to receive the heads after they are severed from the stalks, a beam extending rearwardly from the frame, and dirigible wheel means supporting the rear end of the beam, a platform on the rear end of the beam, a whiffletree adjacent the rear end of the beam.

40 6. In a maize header of the class described, a wheeled frame, a plurality of fingers pro-

jecting forwardly from the frame, a plurality of rollers mounted on the fingers, said rollers being arranged in pairs, means for journaling one roller of each pair so that its axis 55 is rigid, means for journaling the other roller of each pair so that the forward end of its axis may be swung to one side, circuit closers operable by the movements of the second mentioned rollers of the pairs, shafts 60 journaled in the frames, gearing between the shafts and the rollers, gears on the shaft, knives on the gears of the shafts, springs on the shafts having one end fixed to the shaft and the other end fixed to the knives, pivotally mounted latches engaging the gears on the shaft to normally hold them stationary, spring means associated with the latches to hold them engaged with the gears, and electromagnetic means in circuit with the 65 switches for releasing said latches when the latter of the pairs of rollers are swung, an endless inclined conveyor mounted in the frame to receive the heads after they are severed from the stalks, a beam extending rearwardly from the frame, and dirigible wheel means supporting the rear end of the beam, a platform on the rear end of the beam, a whiffletree adjacent the rear end of the beam.

7. In a maize header of the class described, a frame, a pair of rollers mounted on the frame, means for journaling one roller so that its axis is rigid in respect to the frame, means for journaling the other roller so that the forward end of its axis may be swung to one side, a circuit closer operable by the movement of the last mentioned roller, a knife, and means for controlling the operation of the knife from the circuit closer. 80

8. In a maize header of the class described, a frame, a pair of rollers on the frame, means for journaling the rollers on the frame to permit relative movement of the rollers toward and away from each other, a circuit closer operable by the relative movement of the rollers, a knife and means for controlling the operation of the knife from the circuit closer. 85

In testimony whereof I affix my signature.

BIGE GREGORY.
